BATTERY OPERATED POWER PACK

William J. Rakocy, Clifton, N.J., assignor to Ronson Corporation, Woodbridge, N.J., a corporation of New Jersey

Filed Apr. 30, 1965, Ser. No. 85,038

Term of patent 14 years

(Cl. D26—15)

FIG. 1 is a side, top and front perspective view of a battery operated power pack, showing my new design;

FIG. 2 is a top plan view, the bottom being substantially a mirror image thereof;

FIG. 3 is a side elevational view, the opposite side being substantially a mirror image thereof;

FIG. 4 is a rear elevational view; and

FIG. 5 is a front elevational view thereof.

I claim:

The ornamental design for a battery operated power pack, substantially as shown and described.
